UNITED STATES PATENT OFFICE

107,064

DESIGN FOR A PLATE OR SIMILAR ARTICLE

Vincent Broomhall, East Liverpool, Ohio, assignor to The Edwin M. Knowles China Company, East
Liverpool, Ohio, a corporation of West Virginia

Application October 4, 1937, Serial No. 71,955

Term of patent 3½ years

To all whom it may concern:

Be it known that I, Vincent Broomhall, a citizen of the United States, residing at East Liverpool, in the county of Columbiana and State of Ohio, have invented a new, original, and ornamental Design for a Plate or Similar Article, of which the following is a specification, reference being had to the accompanying drawing, forming part thereof,

Figure 1 is a top plan view of a plate or similar article showing my new design, and

I claim:

The ornamental design for a plate or similar article as shown.
